UNITED STATES PATENT OFFICE.

PHILIPPE A. DESLAURIERS AND LOUIS P. DESLAURIERS, OF ST. PAUL, MINNESOTA, ASSIGNORS, BY MESNE ASSIGNMENTS, TO PHILIPPE A. DESLAURIERS AND LOUIS P. DESLAURIERS, COPARTNERS DOING BUSINESS UNDER THE FIRM-NAME OF DESLAURIERS COLUMN MOLD COMPANY, OF ST. PAUL, MINNESOTA.

COLUMN-MOLD.

1,143,107.

Specification of Letters Patent. Patented June 15, 1915.

Application filed July 29, 1909. Serial No. 510,306.

To all whom it may concern:

Be it known that we, PHILIPPE A. DESLAURIERS and LOUIS P. DESLAURIERS, citizens of the United States, residing at St. Paul, 5 in the county of Ramsey and State of Minnesota, have invented certain new and useful Improvements in Column-Molds, of which the following is a specification.

Our invention relates to improvements in 10 means for constructing concrete columns and particularly consists in providing means for so supporting the mold for forming the top of the column that it may be easily taken down without interfering with the supporting frame work for the ceiling mold.

To this end our invention consists in the features of construction, combination and arrangement of parts hereinafter particularly described and claimed.

20 In the accompanying drawings forming part of this specification, Figure 1 is a perspective view of our features of invention arranged in connection with a column mold and ceiling mold; Fig. 2 is a side elevation 25 of the top of the column mold in connection with a ceiling beam mold; Fig. 3 is a detail of a securing block forming part of our invention; Fig. 4 is a top view of the features shown in Fig. 2; Fig. 5 is a detail of a plate 30 forming part of the column top mold; and Fig. 6 is a detail view of removable supporting means for the top of the column mold.

In the drawings the column mold is shown 35 composed of telescoping sections 2, the top section 3 being shaped to form the cap of a column. The top section is formed with an outwardly extending flange 21 forming in use a support for the adjacent ceiling mold 40 plates 4 as indicated in Fig. 1, the ceiling mold plates 4 in turn forming a support for the corrugated ceiling mold plates 5. 6 represents a suitable scaffold or support for the ceiling mold plates, such scaffold being supported as by the standards 7.

In order to permit the removal of the top section of the column mold without interfering with the ceiling mold, we form a free opening 8 in the frame work 6 to receive the 50 column top with brackets 9 supported in the corners of the openings. To support the column top from these brackets we provide a plurality of clamps each consisting of a

jaw 10 to bear against the outer face of one of the brackets and a jaw 11 slidable through 55 an opening 12 in the lower end of the jaw 10. The jaw 11 is adapted to bear against the inner face of the block 3 and to hold the same against the inner face of the framework, the block 13 forming a rest for the 60 flange 21. In the form of column shown, both jaws 10 and 11 are bent to extend away from the brackets and block and permit a tilting movement of the jaws. The opening 12 and the jaw 10, through which the arm of 65 the jaw 11 passes, is inclined and is relatively larger than the arm of the jaw 11 so that with the clamping jaws in the position shown in Fig. 6, the lower end of the jaw 10 being driven inward will grip the arm of 70 the jaw 11 to hold said jaws in clamping position. To loosen the jaws it is simply necessary to drive the lower end of the jaw 10 outward to release and separate the jaws. It will be apparent that with the blocks 13 75 and clamps in position and the column top resting upon the blocks, the column top will be firmly supported in connection with the remainder of the column and ceiling mold, and by loosening the clamps the column top 80 may be taken out of the opening without interfering with any of the ceiling mold plates.

In Figs. 2 to 5 we show means for connecting the top section of the column mold 85 with a beam mold 14. In this adaptation the top column section will be constructed to form one side of the column top and has adjustably secured to its inner edge a band 20 formed with a flange 15 to align with the 90 adjacent side wall of the beam mold. Blocks 16 are secured as by means of screws 17 to the adjacent side of the beam mold and are each formed with an inwardly extending flange 18 to bear against the flange 15 of the 95 plates 20. In this adaptation as in the full top shown in Fig. 1, the top flange 21 is adapted to be supported by blocks corresponding to the blocks 13. The bottom of the top alongside the main column section 100 may be secured to the bottom of the beam mold as by means of adjustable connecting plates 22. In use, in order to outwardly adjust the position of the main column mold with reference to the beam the plates 20 and 105 22 will be adjusted with reference to the

column top to allow said column top to be set outwardly with reference to the beam mold.

By means of the features of construction shown it will be evident that the column mold may be set up in connection with the ceiling molds but may be easily and quickly taken down without interfering in any way with the ceiling molds.

10 The particular means for supporting the column top in connection with the ceiling mold support may be varied without departing from the idea of our invention, the scope of which is defined in the claims.

15 We claim as our invention:

1. Means for forming a unitary column and ceiling comprising movable ceiling molding means formed with an opening, a supporting framework therefor formed with 20 an opening alining with said ceiling mold opening, a mold for the top of the column arranged within said framework opening, an outwardly bent flange carried by the upper edge of said column top mold, and

blocks removably carried by said ceiling 25 mold supporting framework inside said framework opening in position to extend underneath and form a support for said flange.

2. Means for forming a concrete ceiling 30 and connected column comprising in combination a sheet metal mold for forming the top of the column, an outwardly projecting flange carried by the upper edge of said mold, a sheet metal mold plate for said ceiling, a supporting frame-work for said mold plate, blocks fitting underneath said flange to support said column top mold, and clamps 35 removably supporting said blocks from said frame work.

40 In testimony whereof we affix our signatures in presence of two witnesses.

PHILIPPE A. DESLAURIERS.
LOUIS P. DESLAURIERS.
